UNITED STATES PATENT OFFICE.

JOHN SELLERS BANCROFT AND MAURITZ C. INDAHL, OF PHILADELPHIA, PENNSYLVANIA, ASSIGNORS TO LANSTON MONOTYPE MACHINE COMPANY, OF PHILADELPHIA, PENNSYLVANIA, A CORPORATION OF VIRGINIA.

GALLEY MECHANISM FOR TYPE-COMPOSING MACHINES.

1,149,177.

Specification of Letters Patent. Patented Aug. 10, 1915.

Application filed October 24, 1913. Serial No. 797,075.

To all whom it may concern:

Be it known that we, JOHN SELLERS BANCROFT and MAURITZ C. INDAHL, citizens of the United States, and residents of Philadelphia, in the county of Philadelphia and State of Pennsylvania, have invented certain new and useful Improvements in Galley Mechanism for Type-Composing Machines; and we do hereby declare the following to be 10 a full, clear, and exact description of the same, reference being had to the accompanying drawings, forming part of this specification, and to the figures and letters of reference marked thereon.

15 This invention relates to improvements in or upon type composing machines of the class illustrated in Patent No. 625,998, dated May 30, 1899, wherein the composed matter is set up a line at a time, and the successive 20 lines, as produced, are assembled in column form in a galley, and it has for its principal object to facilitate and simplify the conversion of the galley mechanism from a right to a left hand delivery, and vice versa, to 25 the end that the machine may be adapted to compose matter reading from either the left or right of the line.

The machine of the prior patent mentioned is primarily organized and equipped 30 to compose in languages, such as English, in which the characters in each line are read from left to right, and is not adapted without change to set up in complete column form Semitic and like matter wherein the 35 characters are read from right to left of the column or page. To adapt the machine for such matter it has been proposed to assemble the type in the line with the characters inverted, as by forming the cavities of the 40 producing matrices inverted, and, in connection therewith, to equip the galley mechanism so that it will deliver the lines to a galley located upon the opposite or left hand side of the line channel, instead of on 45 the right hand side as in the patented machine. An arrangement of this kind is disclosed in Patent No. 1,061,560, dated May 13, 1913, wherein provision is made for elevating the assembled line above the usual 50 line carrying devices and for transferring it to a galley located on the same side of the line channel as said line carrying devices and above the latter. This involves a very considerable change in the organization, and

a multiplication of elements through the 55 introduction of substitutes, all of which is avoided in the present invention by so equipping the machine that a change from right to left hand delivery can be readily and expeditiously effected by a simple reversal in 60 position of some of the principal operating elements, at the same time eliminating vertical displacement of the assembled line and effecting delivery in the same plane from either side of the line channel as desired. 65

To these ends the invention consists in the novel construction, combination and arrangement of parts hereinafter fully described and pointed out in the appended claims.

In the accompanying drawings illustrating a preferred form of embodiment of said invention—Figure 1 is a top plan view of the improved galley mechanism equipped for right hand delivery of the lines. Fig. 2 75 is an end elevation partly in section of the arrangement illustrated in Fig. 1, part of the frame being broken away to disclose the actuating devices. Fig. 3 is a top plan view of the mechanism as equipped for left hand 80 delivery of the line. Fig. 4 is an end elevation partly in section of the arrangement illustrated in Fig. 3. Fig. 5 is a sectional elevation showing the line transfer for right hand delivery. Fig. 6 is a partial plan 85 view of the supporting and actuating devices for the line carrier and line support retractor, as arranged for right hand delivery. Fig. 7 is a rear view of the line transfer and its support arranged for 90 left hand delivery of the line. Fig. 8 is a top plan view of the line carrier and line support retractor mechanisms reversed in position as compared with Fig. 6, for left hand delivery of the line. Fig. 9 is a rear 95 elevation of the short and long line detector mechanism for right hand delivery. Fig. 10 is a section of said right hand detector mechanism on the line α — α , Fig. 20. Fig. 11 is an end elevation partly in section with 100 the detector mechanism for left hand delivery in position. Fig. 12 is a side elevation of a portion of the actuating lever for the line carrier and line support retractor, showing in section the connection between 105 said lever and the type carrier lever. Fig. 13 is a section view of the type sustaining jaws at the entrance to the line channel with

the type carrier indicated in each of its reversed positions, the galley blade guide being shown in dotted lines. Fig. 14 is a plan view of the line carrier support and actuating slide with the line carrier actuating head shown in full lines in one position and in dotted lines in reversed position. Fig. 15 is an end view of the line carrier support with a part of the supporting guide indicated in section. Fig. 16 is a top plan view of the line support retractor head and actuating levers. Fig. 17 is a side elevation of Fig. 16. Fig. 18 is an end view of the line support retractor head the levers being omitted. Fig. 19 is a perspective of the reversible line carrier. Fig. 20 is a top plan view and Fig. 21 an end elevation of the right hand delivery detector mechanism.

The same numerals represent corresponding parts in the several figures.

The invention is shown by way of illustration as adapted and applied to the machine of Patent No. 625,998, when equipped with the improved galley mechanism of Patent No. 674,375, dated May 21, 1901, to which reference may be had for a more full disclosure.

It will suffice for present purposes to identify some of the principal elements of the mechanism with which the present improvements are more directly associated, such as the type mold 1; type-carrier 2; line channel 3 into which individual type are successively delivered from the type carrier and assembled in line; line carrier 4 for shifting the assembled line and presenting the same to the galley; type sustaining jaws 5, at the entrance to the line channel; galley 6; movable galley blade 7 closing the entrance to the galley and forming one side wall of the line channel; line transferrer 8 forming the opposite side wall of the line channel and movable across the latter to transfer the line to the galley; line support 9 movable longitudinally of the line transferrer; line support retractor 10; galley driving shaft 11 with its ratchet wheel 12; cam head 13 carrying engaging pawl 14; pawl tripping and engaging lever 15; belt shifter 16 with its retaining latch 17; galley blade post 18 and its operating lever 19; and actuating lever 20 coupled with the line transferrer through compression coupling 21.

Save in the particulars hereinafter more fully described and pointed out the equipment of the machine when arranged for right hand delivery as illustrated in Figs. 1 and 2 does not differ in function and mode of operation from prior commercial machines, the improvements introduced being primarily designed to render such a machine readily convertible into one for left hand delivery in the same plane. It is essential to the conversion mentioned that the rela-

tive positions of the galley, galley blade, line carrier, line support and line transferrer shall be reversed, as indicated in Figs. 4 and 5 to the end that the inverted characters composing the lines may be properly delivered to the galley and there assembled in column form; in other words, the line carrier, line support and line transferrer must be located on the side of the line channel previously occupied by the galley blade, and the latter together with the galley must be located on the side of said channel previously occupied by the line transferrer, and at the same time the actuating devices for the galley blade, line carrier, line transferrer and line support retractor must operate in timed relation with said elements under both conditions. To attain these results, and at the same time preserve the general organization of the casting machine as at present constituted, certain changes and additions are required to enable the desired reversal to be accomplished.

As usual the line channel 3 is composed of a fixed floor plate 22 and two side walls 90 formed respectively by the galley blade 7 and line transferrer 8. The receiving end of the galley abuts against the edge of a lateral extension 23 of the floor plate, and after the line carrier has operated to position the line in front of the galley mouth or entrance the galley blade is elevated and the line transferrer is advanced to move the line laterally beneath the elevated galley blade and deposit it in the entrance to the galley, after which the galley blade is partly lowered, to engage and retain the expelled line while the line transferrer is retracting. The line carrier 4 traverses longitudinally of the line channel on the side 95 thereof occupied by the line transferrer. The line support 9 traverses in a way on the line transferrer and said support or the line cooperates with a trip mechanism located on the galley side of the line channel, 100 to release the belt shifter retaining latch 17 and thereby stop the machine whenever the line acted upon by the transferrer is either over or under the measure. The problem presented is to so organize and 105 construct these cooperative members that they may operate in reversed relation for right and left hand delivery in the same plane. The line transferrer of the present 110 commercial machines is an integral structure comprising a horizontal member or bar provided with a way or groove in one face for the reception of the line support 9 and a stem or carrying member engaging 115 bearings on the frame beneath the floor plate of the line channel. The horizontal member forms one side of the line channel, and expands beyond the journal bearings in 120 an unequal degree at opposite ends so that its position cannot be reversed from one 125

side to the other of the line channel. To overcome this and provide a transferrer of sufficient length to transfer the longest line which may be composed in the machine the 5 horizontal or line channel member of the present machine is formed in two sections, whereof the main or body section attached to the supporting stem or lever is formed symmetrical, that is, its extremities are equi- 10 distant from the corresponding journal bearings 25, Figs. 5 and 7, so that it may be reversed and still maintain its relation to the type sustaining jaw 5 located on the same side of the line channel, the support 15 for said jaw forming part of one side of the galley entrance. The other section 8^x forming the outward extension of the line transferrer remote from sustaining jaws 5 is adapted for attachment to either end of 20 the main or body section, as by providing each end of the latter with a seat 26 to which a central longitudinal rear extension or web 27 of the section 8^x is detachably secured, as by bolts 28, this connection being 25 supplemental and reinforced, if found necessary or desirable, by a dowel joint 29 (Fig. 3) and interlocking or mortise joint 30, Fig. 5. As thus constructed when it is desired to reverse the position of the line 30 transferrer it is only necessary to detach the outer section 8^x, turn the main or body section 8 about a vertical and the extension section 8^x about a horizontal axis, apply said extension section to what is now the outer 35 but before was the inner end of the main section, and apply the main section to its bearings.

When arranged for normal or right hand delivery, Figs. 1 and 2, the compression coupling 21 directly engages the line transferrer and is held in engagement with the cam head 13 by a retracting spring 31, as shown in Fig. 2. A reversal of the line transferrer for left hand delivery (Figs. 4 and 5) renders this connection inoperative inasmuch as the direction of the motion controlled by the cam is now reversed. To reestablish the connection, the stem of the line transferrer is provided with a pivot 33 for the reception 50 of a lever 34, one arm whereof engages compression coupling 21 and the opposite arm engages an adjustable bearing 35 on the frame. Upon connecting retracting spring 31, to lever 34, Fig. 4, it operates to retract 55 the line transferrer by holding lever 34 in engagement with bearing 35 and coupling 21 respectively so that the cam operates, as before, to control the movements of the transferrer.

60 A reversal in the position of the line transferrer necessitates a corresponding change in the galley blade forming the opposed wall of the line channel, to accomplish which an adjustable or extensible connection is made 65 between said blade and its post 18. Such

an adjustment is provided by forming the connection between the blade and its head or socket member 36 in two detachable and longitudinally movable sections united by suitable means, such as clamping screw 37. 70 By loosening said connection the galley blade can be set to either side of the line channel and adjusted to the desired width thereof, its inner end riding in a guide 18^x adjustably mounted as upon one of the sustaining jaws 5, said guide being adjusted to the predetermined width of the line channel. It may be noted in this connection that the sustaining jaws 5 at the entrance to the line channel are separately adjustable, laterally of said channel, for which purpose and to permit the passing of the line carrier hooks both jaws 5 conform in structure to the adjustable jaw 5 in Patent No. 1,024,492, and said jaws are each arranged 80 for independent adjustment transversely of the line channel to accommodate different size type for either right or left hand delivery. 85

The jaws of the line carrier 4 embrace and traverse longitudinally of the sections of the line transferrer constituting a wall of the line channel, hence a reversal in position of said transferrer involves a corresponding change in the position of the line carrier as 90 well as of the line support 9. In the case of the line support it is of the usual construction, but if it is to be reversed it may be supplied with a notch at each end instead of at one end only so as to permit of transposition when the line transferrer is reversed. In the case of the line carrier, however, an impediment to reversal exists in the lateral extension 23 of the line channel floor plate and the relation which the hooks 105 bear to the actuating mechanism therefor. These obstacles are overcome and the line carrier rendered operable on either side of the line channel, and by the same actuating devices, in the following manner: In the first place the lateral extension 23 of the floor plate is made separate and removable from the floor plate proper, and supports or guides 40 are provided on opposite sides of the floor plate for the reception of said plate 110 or extension. In the second place the head of the line carrier from which its hook members project is coupled with the actuating head or member 41, (see Figs. 14 and 15) through which motion is communicated to 115 said line carrier, in a manner to permit of the inversion of the line carrier about a horizontal axis and a reversal of the head 41 about a vertical axis. A simple and effective form of coupling is shown, wherein 120 head 41 is furnished with one or more dowel pins 42 and the head of the carrier with corresponding apertures 43 (Fig. 19).

Mounted to reciprocate in guides beneath the floor plate are two heads or blocks 44, 45, 130

arranged in tandem, the first serving as a support for the line carrier and the second for line support retractor 10. Head 44 is provided with two bearings 46 symmetrically disposed on opposite sides of the floor plate. These bearings are each adapted to receive a removable pivot pin or bolt 47, the latter serving both as the pivot of the line carrier and as means for confining said carrier in adjusted position with relation to head 41. Head 44 is further supplied with two sets of stops or abutments 48 for limiting the oscillatory motion of the carrier about its pivot and for transmitting motion to said head.

Guided to reciprocate beneath the floor plate is a slide 49 provided with opposed bearings 50 between which, at a point midway between bearings 46, they engage on opposite sides of the line carrier actuating head 41. As thus arranged when it is desired to change from right to left hand delivery, or vice versa, bolt 47 is first removed from that one of the bearings 46 at the time engaged, the carrier is inverted, and the head 41 thereof reversed in position, after which the bolt 47 and the reversed carrier is applied to opposite bearing 46.

The inward motion of head 44 toward the entrance to the line channel is limited by a stop or abutment 51, Fig. 6, while its outward travel is limited by an adjustable stop 52 (Fig. 1), the latter arranged in line with an extension 52^x (Figs. 11 and 14) of the head and determining the delivery point of the inner end of the line in its relation to the galley entrance. During the inward movement of slide 49 the carrier is oscillated, to retract its hooks from the line channel, before motion is communicated to head 44 to transport the carrier toward the entrance of the line channel, and its inward movement is arrested with the hooks still retracted and in position to enter the line channel behind the last type in the line immediately the motion of slide 49 is reversed.

Head 45 is also provided with two bearings 53 (Figs. 6, 8, 16, 17 and 18) one on each side of the floor plate, and in each bearing is mounted one of two bell crank levers 54, 55, the inner or proximate arms whereof are jointed together beneath the floor plate while the opposite arms extend longitudinally on opposite sides of the line channel. The outer end of each lever 54, 55 is provided with a bearing 56 for line support retractor 10, the latter provided with a retracting spring 58 for holding it in yielding engagement with a shoulder 59 on lever 54 or 55, and projecting into the path of the line support 9 in rear of the latter. Retractor 10 is adapted for application to the bearing 56 of either lever and should occupy the one nearest the line transerrer.

It is obvious that motion communicated to

either lever 54, 55 in a direction to reciprocate head 45 will be transmitted to the other and will operate to either withdraw retractor 10 from the path of the line support or insert it therein before motion is communicated to head 45.

Alternative forms of removable short and long line detectors are provided for right and left hand delivery, both adapted for similar action upon latch 17 in effecting a stoppage of the machine. These detectors coöperate with the type and line support in the type channel just as in the commercial machine now in extensive use; that is to say, a detector will, if the line be too short, be struck by the line support when the latter is moved by the transerrer, and if the line be too long, it will be struck by the end type of the line. In either event it is forced back as the transerrer advances and, through connections to be presently described, trips the latch and arrests the operation of the machine.

The short and long line detector is, as heretofore, provided with a narrow or tongue member 61 for coöperation with the furcated end of the line support. For right hand delivery (Figs. 1, 2, 9, 10, 11, 20 and 21) this tongue member is mounted in guideways in a head 62, the latter adjustable longitudinally of the line channel in ways on a frame 63, as indicated in Fig. 2. This frame 63 is also adjustable longitudinally of the line channel on the floor plate, thus providing a double or telescopic adjustment for head 62 and its contained tripping member 61. Head 62 is removably secured in adjusted position on frame 63 and the latter on the floor plate by suitable retaining devices 64 and screw bolts 65. Tripping member 61 is adjusted in relation to the support for the sustaining jaw 5 on the same side of the line channel to correspond with the measure of the matter to be composed.

Motion is transmitted from the member 61 to retaining latch 17 for releasing the stopping mechanism through rack teeth on said member engaging a gear segment 67 fast on a shaft 68, the latter mounted in bearings on head 62 to follow the adjustments of the latter. Shaft 68 has an angular section movable longitudinally through a pinion 69 journaled in frame 63. Pinion 69 engages a gear sector 70 fast on shaft 71, the latter mounted in bearings on frame 63 and provided with an angular section on which is supported the hub of a lever 72 journaled in a bracket 73 detachably secured to the side of the floor plate.

Lever 72 is connected through a detachable link 74 to one arm of a lever 75, the latter pivotally supported upon the frame and provided with bearings for the reception of the pivot 76 of latch 17. Threaded through a vertical extension of said latch

and bearing upon lever 75 is an adjusting screw 77 for varying the angular relation of latch 17 to lever 75, the connection being maintained by spring 78 applied to latch 17 above its pivots on lever 75, said spring also operating to hold the latch in engagement with the complementary member 16 of the stopping mechanism.

When pressure is applied to retract member 61 it will, through the mechanism described, cause a withdrawal of latch 17 and permit the stopping mechanism to operate.

The machine is also equipped with a detector adapted for left hand delivery. In the present instance this includes a guide 80, (Figs. 1, 2, 3, 4 and 11) supported in bearings 81 and bridging the entrance to the galley. Adjustably secured to guide 80 and resting upon the floor plate extension 23, when in position, is a head 82 containing guides for the reception of the movable tongue or tripping member 61*. Journaled in the head 82 is a shaft 83 to the inner end of which is attached an arm 83* (dotted lines Figs. 4 and 11) engaging member 61*. The outer end of shaft 83 of angular section passes loosely through the hub of a lever 84 journaled in outer bearing 81 thus accommodating itself to the adjusted position of said head 82 transversely of the galley entrance. Lever 84 is connected by a link 85 to one arm of a lever 86, the opposite arm whereof is coupled by a link 87 with retaining latch 17. Either detector mechanisms can be removed at will by the uncoupling of any of the connecting links or otherwise as desired.

The actuating devices for the line carrier and line support retractor have been changed and improved to harmonize in action with either direction of line delivery, and this too without material change or alteration in the groove of the cam head heretofore employed in single delivery machines.

The new actuating mechanism includes two levers 90, 91, pivoted at one end to the frame. The outer or free end of lever 90 engages between bearings 92 on slide 49 of the line carrier devices (Figs. 4, 8 and 14) while the corresponding end of lever 91 is coupled through an adjustable link 93 with an arm 94 of bell crank lever 54 pertaining to the line support retractor. A lever 95 pivoted upon the frame has one of its arms equipped with a roller 96 working in groove 97 in the cam head and with a link 98 whose opposite end is connected to lever 91, whereby the motion communicated by the cam to lever 95 is transmitted to lever 91. Lever 90 is also coupled with the actuating lever 95, through a double acting compression device, the same comprising a head or plate 99 provided with oppositely arranged slots 100 each containing a pin

101 fast on lever 95. At a point intermediate slots 100 head 99 is connected by a link 102 with lever 90. Head 99 is provided with an arm 103 which latter is connected to an arm 104 of lever 95 through a spring 70 105. The arrangement is such that in a normal or unrestrained condition head 99 will be tilted by spring 105 to cause the opposite ends of the two slotted portions to engage pins 101, and owing to the intermediate location of link 102 with relation to said pins, pressure exerted upon said link in either direction and sufficient in degree to overcome the tension of spring 105 will cause head 99 to oscillate upon one or the other pin as a fulcrum.

The various parts are so adjusted in their relation to the controlling cam groove that when latch or pawl 14 is disengaged and the galley mechanism thereby brought to rest at 85 the completion of its cycle of movements, the hooks of line carrier 4 will stand retracted at the inner end of the line channel and the line support retractor 10 although in advanced position will also be withdrawn from 90 the path of the line support. This result is attained by causing the head 44 of the line carrier to engage abutment 51 before actuating lever 95 completes its movement toward the center of the cam head, thereby effecting a displacement of head 99 and exerting the pressure upon lever 90 through spring 105, followed by a slight outward movement of lever 95 sufficient in degree to turn levers 54, 55, upon their pivots to effect the withdrawal of retractor 10 from the line channel, but insufficient to relieve the pressure of spring 105 by permitting contact of head 99 with both pins 100. In other words, the galley mechanism is brought to rest at the 105 beginning of the outward stroke of actuating lever 95 and while head 44 of the line carrier is still held in its extreme position under elastic pressure exerted by spring 105 through the previously displaced head 110 99. By locating the connections between levers 95 and 90 at points respectively nearer the pivot of the former and remote from the pivot of the latter, and the connection between levers 95 and 91 at points respectively 115 more remote from the pivot of 95 and nearer the pivot of 91, the motions communicated to said levers 90, 91, from the same cam will differ both in extent and speed, with the excess in favor of lever 91. This excess of 120 motion is provided to effect the retraction of the line support retractor 10 at a speed greater than that of the line carrier and to a point some distance beyond that to which the line support is moved when engaging member 61 (or 61*) is set to the maximum measure, and so that upon the return or inward movement of lever 91 said member 10 will be projected across the line channel in position to engage the line support and return 130

the latter to its initial position and withdraw from the line channel so as to leave the latter clear for the assembling of the next line by the pusher.

5 The galley 6 is supported on cross bars 107 on either side and with its upper surface in the plane of that of the floor plate, its inner end abutting against the outer edge of extension 23, and with the inner face of its 10 rear or inner side bar 108 flush with the outer margin of either one of the supports for sustaining jaws 5. The adjustable side bar 109 is provided with a centrally located tongue 110 for engaging a seat in head 62 or 82 so that when applied to either of said 15 heads its inner face will be in alignment with that of the head, the latter forming the outer wall of the galley entrance.

From the foregoing description it is apparent that without any radical change in the action or mode of operation of the galley mechanism when once adjusted, it has been endowed with a dual capacity, that of effecting either right or left hand delivery 20 of the composed lines of type. Save in the respect mentioned the galley mechanism as a whole operates as heretofore, that is to say, the type for each line of composition are delivered one at a time from the type carrier into the line channel while the galley mechanism is at rest, with the line carrier near the entrance to the line channel and at one side thereof, and the line support retractor at the inner end of its travel and 25 to one side of the line channel.

After the line is completed by the delivery of the last type thereof into the line channel, the galley mechanism is automatically started into action by the engagement 30 of pawl 14, and operates to first project the line carrier hooks across the line channel, in rear of the last type delivered, and then move outward until the inner end of the line registers with the inner wall of the 35 galley entrance. If the line is correct to measure its outer end will now register with the outer wall of the galley entrance and the groove of the line support will register with the tongue of the detector. But if the line 40 is short the line support will stand in position to engage the detector and if long, the type will stand opposite said detector. During this outer movement of the line carrier, the line support retractor has moved 45 outwardly in the same direction but to a greater distance. The galley blade is next elevated to uncover the galley entrance and the line transferrer is advanced across the line channel to deposit the line in said galley 50 entrance at the same time advancing the composed column in the galley. This action takes place if the line is true to measure; if not the detector is brought into action to 55 stop the machine. After the delivery of a 60

correct line, the galley blade partly descends to support the type; the line transferrer retracts; the galley blade descends its full stroke; the line carrier and line support retractor are returned to the inner end of the line channel, the hooks of the line 65 carrier being first moved out of the line channel to pass any type which in the meantime may have been deposited therein, and the line support retractor having been moved across the channel to engage the line 70 support and move it to initial position; after which said retractor is withdrawn 75 from the line channel and the galley mechanism brought to a standstill.

Having thus described our invention, 80 what we claim as new and desire to secure by Letters Patent of the United States, is:

1. A galley mechanism for type composing machines embodying a type channel, means for advancing the composed line of 85 type longitudinally of the channel, and means for transferring the composed lines bodily to either side of the channel to form a right or a left hand column.

2. A galley mechanism for type composing machines embodying a type channel and a laterally movable line transferrer reversible to occupy a position on either side of the channel.

3. A galley mechanism for type composing machines embodying a type channel embodying a line carrier movable longitudinally of the channel and reversible to occupy a position on either side of the channel.

4. A galley mechanism for type composing machines, embodying a type channel, a galley blade adjustable transversely of the channel whereby it may be positioned on either side of the channel, and means for 105 moving the blade vertically to permit of the transfer of a composed line past the blade.

5. A galley mechanism for type composing machines including, in combination, a 110 galley blade and opposed line transferrer forming side walls of a line assembling channel and transposable for effecting either right or left hand delivery of the line.

6. A galley mechanism for type composing machines including, in combination, a galley blade and opposed line transferrer forming side walls of the line assembling channel and transposable to effect either right or left hand delivery, and a line carrier movable longitudinally of the line channel and adapted for operation on either 120 side of the latter.

7. A galley mechanism for type composing machines including, in combination, opposed galley blade and line transferrer constituting side walls of the line channel and transposable to effect right or left hand de- 125

livery of the line, a line carrier movable longitudinally of the line channel on either side thereof, a line support carried by the line transfer, and retracting mechanism 5 for said line support.

8. In a galley mechanism for type composing machines, the combination of the following elements, to wit: a laterally adjustable galley blade; a reversible line 10 transposer adapted for position on either side of the galley blade; and a reversible line carrier.

9. In a galley mechanism for type composing machines, the combination of the following elements, to wit: opposed galley blade and line transposer forming side walls 15 of a line assembling channel and transposable to effect either right or left hand delivery; a reversible line carrier pivotally supported to oscillate laterally and reciprocate bodily longitudinally of the line channel; and a reciprocating supporting head provided with duplicate carrier supporting 20 bearings symmetrically disposed on opposite sides of the line channel.

10. In a galley mechanism for type composing machines, the combination of the following elements, to wit: movable galley blade and a movable line transposer arranged in parallel to provide a line assembling channel there-between, said members being transposable to effect either right or left hand delivery of the line; a line carrier movable laterally and longitudinally of the 30 line channel to engage and transport the line therein; and means for supporting and actuating said carrier when located on either side of the line channel the same comprising a head guided to reciprocate longitudinally of the line channel and provided with a plurality of bearings for the reception of the line carrier.

11. In a galley mechanism for type composing machines provided with opposed galley blade and line transposer transposable in position and forming side walls of the line channel and in combination therewith, a pivoted and reversible line carrier provided with a reversible actuating member or arm; a head reciprocating parallel with the galley blade and provided with two carrier receiving bearings one on each side of the line channel; and a slide for engaging the actuating arm of the line carrier, to oscillate and reciprocate the latter when mounted upon either bearing on said head.

12. In a galley mechanism for type composing machines provided with a line assembling channel formed between a galley blade and a line transposer transposable mounted in parallel relation, and in combination therewith, a line support mounted on the line transposer; a reversible line carrier, and a supporting head provided with dupli-

cate bearings and duplicate sets of limiting 65 stops for said carrier.

13. In a galley mechanism for type composing machines, the combination of the following elements, to wit: a reciprocating head provided with duplicate bearings disposed transversely of its line of motion; and a reversible line carrier adapted to be pivotally supported in either bearing on said head and provided with a reversible actuating member or arm through which motion is applied to oscillate the carrier on its pivot and reciprocate the supporting head.

14. In a galley mechanism for type composing machines, the combination of the following elements, to wit: a reciprocating 80 head provided with a plurality of bearings; a reversible line carrier adapted to be pivotally supported by either of said bearings and provided with a reversible actuating arm or member; two limiting stops in proximity to each of the bearings on said head between which stops the actuating arm of the carrier is projected; and a slide provided with spaced shoulders or abutments for engaging the actuating arm of the line carrier 85 when the latter occupies either of the bearings in said head.

15. In a galley mechanism for type composing machines provided with a line assembling channel comprising a floor plate and opposed side walls formed of transposable galley blade and line transposer, and in combination therewith, a reversible line carrier provided with a reversible actuating member or arm; a head movable longitudinally of the line channel and provided with a plurality of bearings and associated sets of stops or abutments for limiting the movements of the carrier toward and away from the line channel and to transmit motion in 100 either direction to said head, and a slide provided with opposed engaging bearings or abutments located intermediate said bearings on the head and operating to first oscillate the line carrier on its head and then 110 transmit motion to said head and carrier.

16. In a galley mechanism for type composing machines, the combination with a laterally adjustable galley blade forming a side wall of the line assembling channel, of a line 115 transposer forming the opposite wall of said channel and adapted for location on either side of said galley blade, said line transposer comprising a body portion symmetrically disposed with relation to its bearings and reversible in the latter, and an extension section adapted for detachable attachment to either end of the line channel section of said body portion.

17. A line transposer for the galley mechanism of a type composing machine, the same comprising, in combination, a body portion provided with bearings and a line

channel section symmetrical with said bearings, and a detachable extension member for the line channel section adapted for application to either end of the line channel section of the body portion.

18. In a galley mechanism for type composing machines the combination of the following elements to wit: a floor plate provided with a detachable extension for application to opposite edges thereof; spaced type sustaining jaws at one end of the floor plate; a vertically movable galley blade extending longitudinally above the floor plate, and adjustable laterally thereof to register with one or the other sustaining jaw; and a horizontally movable line transerrer paralleling the galley blade and reversible to face either side of the galley blade.

19. In a galley mechanism for type composing machines, the combination of the following elements to wit: a floor plate; spaced sustaining jaws located at one end of the floor plate and forming the entrance to the line channel; a movable galley blade forming one wall of the line channel and laterally adjustable to register with either sustaining jaw; a movable line transerrer reversible on its bearings to face either side of the galley blade and register with either sustaining jaw; a head guided to reciprocate longitudinally beneath the floor plate and provided with a plurality of bearings, one on each side of the floor plate; a pivotal and reversible line carrier adapted for application to either of said bearings; and an actuating slide engaging said line carrier to oscillate and transport the latter.

20. In a galley mechanism for type composing machines, the combination of the following elements to wit: a laterally adjustable galley blade and a reversible line transerrer together forming opposite walls of a line assembling channel; a head movable longitudinally of said channel and provided on each side thereof with a bearing and pair of associated stops or abutments; a reversible line carrier adapted for pivotal attachment to either of said bearings and provided with an actuating arm adapted to enter between the stops associated with the bearing so occupied; and a slide provided with shoulders between which the line carrier actuating arm is engaged when said carrier is mounted upon either bearing.

21. In a galley mechanism for type composing machines, the combination of the following elements to wit: a floor plate; type sustaining jaws at one end of said plate and removable detector heads at the opposite end thereof, to provide galley entrances on opposite sides of the floor plate; a laterally adjustable galley blade bridging the interval between either one of said sustaining jaws and the complementary detector head; a reversible line transerrer adapted

to register at one end with the remaining sustaining jaw to form in conjunction with the galley blade a line assembling channel disposed on either side of the galley blade, said line transerrer extending beyond and overlapping the retained detector head next the galley blade; and a reversible line carrier movable laterally and longitudinally of the line channel.

22. A short and long line detector mechanism for a type composing machine provided with a latch controlling the power transmitting devices to uncouple the same, including in combination the following elements, to wit: a head adjustably secured to an adjustable frame; a movable detector member mounted on said head and provided with a rack; a shaft journaled in the detector head and carrying a gear segment engaging said rack; a pinion journaled in said adjustable frame and coupled with said shaft to permit longitudinal movement of the latter; a second shaft journaled in said adjustable frame and carrying a gear segment in engagement with the last named pinion; a lever journaled in a fixed bearing and embracing said second shaft to permit longitudinal adjustment; and means for coupling said lever with the power controlling latch.

23. In a galley mechanism for type composing machines equipped with a reversible line transerrer having a stem and an actuating cam and interposed coupling, and in combination therewith, a lever removably supported on the stem of the line transerrer, and an adjustable bearing on the frame to receive one arm of said lever, the opposite arm thereof being engaged by the coupling, the arrangement being such that when the line transerrer is in one position of adjustment it is controlled from the cam through the coupling, the latter applied directly, and when in reversed position the motion of the coupling as derived from the cam is transmitted through the said lever whereby the same cam and coupling exercise control over the transerrer in both positions of adjustment.

24. In a galley mechanism for type composing machines provided with a line assembling channel and means for supporting a galley on either side thereof, and in combination therewith, a movable galley blade forming a side wall of the line channel, an actuating post for said galley blade and an extensible coupling between said galley blade and actuating post adapted to permit the galley blade to be shifted from one side to the other of the line assembling channel.

25. In a galley mechanism for type composing machines provided with a line assembling channel including a reversible and laterally movable line transerrer and an opposed laterally adjustable and vertically

- movable galley blade, a reversible line carrier and a line support both movable longitudinally of the line channel, and a galley located in rear of the galley blade, and in 5 combination therewith, actuating devices adapted to operate in timed relation to the line transerrer when located on either side of the line channel, adjusting means for locating the galley blade on either side of 10 the line channel; means for sustaining the galley on either side of the line channel in rear of the galley blade; means adapted to receive the line carrier and to actuate the latter for either right or left hand delivery; and means for receiving a line support 15 retractor and actuating the same on either side of the line channel.
26. In a galley mechanism for type composing machines equipped with a line channel including opposed line transerrer and galley blade, and a line carrier movable longitudinally of said channel, the combination of the following elements, to wit: actuating devices adapted to operate the line trans- 20 ferrer for right or left hand delivery of the line; a reversible line carrier and means adapted to operate the same from either the right or left of the line channel; and a galley blade adjustable with relation to its sup- 25 porting post to occupy a position on either side of the line channel in opposition to the line transerrer.
27. In a galley mechanism for type composing machines, the combination with op- 30 posed transposable type transerrer and galley blade forming side walls of the line assembling channel and a line support movable longitudinally of the line transerrer, of a line support retracting means including 35 a slide movable longitudinally of the line channel; two levers articulated together mounted upon said slide and extending on opposite sides of said channel; and a retrac- 40 tor adapted for application to one or the other of said levers accordingly as the machine is arranged for right or left hand delivery of the line.
28. In a galley mechanism for type composing machines, provided with a line as- 45 sembling channel the side walls whereof include opposed transposable movable line transerrer and movable galley blade mem- 50 bers, a line carrier movable into and out and longitudinally of said channel, a line sup- 55 port also movable longitudinally of said channel, and a retractor for said line support movable into and out of engagement with the latter and longitudinally of the line channel, and in combination therewith, ac- 60 tuating mechanism for said line carrier and retractor the same including two levers, one for the line carrier and the other for the re- tractor, an actuating cam, a lever provided with a cam engaging member and linked to one of said first named levers, a plate linked 65 to the second of said levers and provided with oppositely located slots, pins passing through said slots and engaging the cam operated lever, and a spring interposed between the last named lever and said slotted 70 plate.
29. In a galley mechanism for type composing machines, an actuating mechanism for the line carrier and line support comprising, in combination, the following ele- 75 ments, to wit: a controlling cam; a lever coupled with said cam and reciprocating thereby; pins on said lever; an actuating lever coupled with said cam controlled lever; a second actuating lever; a plate or member 80 provided with opposite slots engaged by said pins on the cam controlled lever and coupled at a point intermediate said slots with the second lever; and an elastic cou- 85 pling between said slotted plate or member and the cam controlled lever.
30. A galley mechanism for type composing machines equipped to receive a reversible line transferring member, and in combination therewith, a movable galley 90 blade provided with means for setting or adjusting the same on either side of the line assembling channel in opposition to the line transerrer; a reversible line carrier located on the same side of the line channel as the 95 line transerrer; and means for supporting a galley in the same plane on either side of the line channel.
31. In a galley mechanism for type composing machines, provided with a line as- 100 sembling channel comprising a floor plate, and opposed laterally movable line transerrer and vertically movable galley blade, and in combination therewith, a support mounted in fixed position above the floor 105 plate parallel with and in rear of the galley blade, a head movably secured to said support, a trip carried by said head, a latch controlling the driving mechanism and means for coupling the trip and latch for 110 actuating the latter.
32. In a galley mechanism for type composing machines and in combination with the galley blade, line transerrer and a restraining latch for the power controlling de- 115 vices thereof, of a line trip adjustably attached to a support mounted in fixed position bridging the entrance to the galley in rear of the galley blade.
